(No Model.)

B. YOCH.

Mining Machine.

No. 242,734.

Patented June 7, 1881.

N. PETERS, Photo-Lithographer, Washington, D. C.

UNITED STATES PATENT OFFICE.

BENHARD YOCH, OF WEST BELLEVILLE, ILLINOIS.

MINING-MACHINE.

SPECIFICATION forming part of Letters Patent No. 242,734, dated June 7, 1881.

Application filed February 24, 1881. (No model.)

To all whom it may concern:

Be it known that I, BENHARD YOCH, of West Belleville, St. Clair county, Illinois, have invented a certain new and useful Improvement 5 in Mining-Machines, of which the following is a full, clear, and exact description, reference being had to the accompanying drawings, making part of this specification.

My improvement belongs to that class of 10 mining-machines supported upon two side wheels on which the cylinder has capacity for horizontal and vertical oscillation.

The first part of my improvement consists 15 in a crank-connection between the wheels and the pick-cylinder, to enable the latter to be placed at a higher or lower elevation.

The second part of my improvement consists 20 in making the crank of the axle adjustable in length.

The third part of my improvement consists 25 in the described means for holding the cylinder to the vertical position in which it may have been placed by the adjustment of the crank-axle, said means consisting of two rods sleeved upon the axle-spindles at the fore ends 30 and connected to the cylinder by pins passing through pin-holes in the rods and into the cylinder-casting, the rods having each a number of pin-holes for adjustment. These rods, at the rear ends, project in the form of handles, by which the machine is moved.

The fourth part of my improvement consists 35 in the combination, with a single piston, of two piston drill-rods working in a guide-frame attached to a turn-disk, which constitutes the central part of the cylinder-head.

The fifth part of my improvement consists 40 in the combination, with the duplicate piston-rods, of a head having sockets to contain the picks.

The sixth part of my improvement consists 45 in a spring friction-brake to prevent the retrograde movement of the machine.

The seventh part of my improvement consists 50 in providing the cylinder with separate ports for the induction and eduction of air or steam to and from the cylinder-chamber, and placing the eduction-ports a sufficient distance from the ends to cushion the piston at the ends 55 of the strokes. In connection with this the valve consists of two hollow portions or D-

valves opening and closing the exhaust-connection, and two flat lapping portions working in conjunction with the induction-ports at the ends of the cylinder.

The eighth part of my improvement consists 55 in the combination of two cutting tools or picks, made each with two inclined cutting-edges and inwardly-extended wings, as hereinafter more fully described.

The ninth part of my improvement consists 60 in the combination of a mining-machine and metallic platform with side guides, for the purpose set forth.

Figure 1 is a perspective view of the machine with the picks removed. Fig. 2 is a longitudinal section of the pick-engine cylinder and its valve-chest at x x , Fig. 3. Fig. 3 is a transverse section of the cylinders and valve-chests at x' x' , Fig. 2. Fig. 4 is a detail horizontal section at jogged line x^2 x^2 , Fig. 2, showing the lamp and part of the guide-frame in top view. Fig. 5 is an under view of the drill-socket head and the ends of the pick-rods, (or piston-rods.) Fig. 6 is a perspective view of the socket-head, showing three picks in position. Fig. 7 is a perspective view of a single broad-ended pick. Fig. 8 is a perspective detail of the brake mechanism which prevents the retrograde movement of the machine, and Fig. 9 is a section of same, with part in side elevation. Fig. 10 is a view of the upper end of a guide-standard of the hand-rods, by which the brakes are removed from the wheels to allow their retrograde rotation; and Fig. 11 is a side view of same with the end of a rod in position within it. Fig. 12 is an axial section through the hub of one wheel, showing the crank-extending device. Fig. 13 is a perspective view of a supplementary socket-head. Fig. 14 is a horizontal section of the front head of the cylinder.

A is a platform, which is laid upon the floor of a room in the mine, and which supports the machine. The platform consists of a flat sheet of metal with side guides, a , which serve to 95 retain the wheels upon the platform.

a' are loops or hooks, by means of which the platform may be moved by crow-bars or otherwise.

B are wheels, on which the cylinder and other parts are supported. The wheels turn on sleeves or skeins, which have capacity for 100

oscillatory movement on the spindles *c* of the crank-formed axle *C*. The journal of the crank occupies a bearing-box, *D*, attached to the top of the valve-chest *E* upon the top of the cylinder *F*, thus forming the means of support of the cylinder and attached parts. As the cylinder is supported on the crank-axle the elevation of the cylinder may be changed by turning the crank up or down, and the relative position of the cylinder to the wheels may be otherwise changed by the same means. The wheel-spindles *c* of the axle are not made in one piece with the crank, but carry sockets *c'*, in which the side arms, *c²*, of the crank admit of endwise adjustment to regulate the length of the crank, thus adjusting the distance between the box *D* and the spindles *c*, and consequently the relative position of the cylinder *F* and the wheels *B*. The arms *c²* are secured in the sockets *c'* by set-screws *c³*.

To retain the crank to its adjustment rods *G* are provided, of which the sleeves *G'* (surrounding the spindles *c* within the wheel-hubs) form the forward ends. The arms *G* extend backward beside the cylinder, and have series of cavities *g* for the reception of the point of a set-screw, *H*. Said screw passes through a keeper, *H'*, into one of the depressions *g*, and holds the arms, the cylinder *F*, and the crank firmly in their relative position, the three parts mentioned forming a sort of triangular brace. The arms *G* end at the rear in handles *G²*, by which the machine is moved.

Upon the wheels *B* are friction-rings *I*, which may be secured to the spokes, as shown, or to other part of the wheel, or may be cast upon it.

J is an arm extending from the sleeve *G'*, and having on it a fulcrum lug or lugs, *j*, to which is hinged a brake-lever, *K*. The outer end of the lever carries a brake-shoe, *k*, which, when the top of the lever is in its backward position, bears upon the friction-ring and prevents the backward rotation of the wheel.

L is a spring, which tends to hold the brake-shoe down upon the ring by pushing the lever into its backward position. The brake-shoe is lifted from the ring *I* by drawing backward a rod, *M*, which is attached to the lower end of the lever, and which works in a standard, *N*, upon the arm or rod *G*. The rod *M* has an enlargement at *m*, which works in a suitable eye, *n*, at the upper end of the standard. At the lower side of the eye *n* is a notch or socket, *n'*, of a size to receive the part of the rod in front of the enlargement. When the rod is drawn back far enough the part of the rod before the enlargement may be dropped into the notch *n'*, and the brake-shoe thus held away from the friction-ring *I*.

O The compressed air enters the valve-chest *E* through a pipe, *O*, which may be provided with a throttle-valve. (Not shown nor claimed.) The compressed air fills the valve-chest *E* and passes through a duct, *P*, from the valve-chest *E*, into the valve-chest *R* of the small engine *S*, which works the slide-valve *V* of the pick-

engine. The duct *P* is provided with a cock or valve, *Q*, to regulate the speed of the small engine *S*, and, as a result, to regulate the speed of the pick-engine. By closing the valve *Q* both engines may be stopped, thus rendering a valve in pipe *O* unnecessary. The piston-rod *s* of the engine *S* is connected by rod *s'* to a crank, *t*, upon a shaft, *T*, carrying eccentrics operating both slide-valves—that is to say, the slide-valve of engine *S* and the slide-valve *V* of the pick-engine. The engine *S* contains no feature of novelty, being of a common form of reciprocating engine, and needs no particular description. The crank-shaft *T* extends through the valve-chest *E*, passing through stuffing-boxes in the sides of the chest.

U is an eccentric on the shaft *T*, connected by a rod, *U'*, to the bar *V'*, which connects together the members of the valve *V*. *T'* is a fly-wheel on the shaft *T*. The slide-valve *V* has at each end a flat-faced lap-valve, *v*, and a **D**-valve, *v'*, the former working in conjunction with the induction-ports *F'*, and the latter in conjunction with the eduction-ports *F²* and the exhaust-duets *F³*, the latter leading through the side of the cylinder-casting to the outer air. The eduction-ports *F²* are some distance (say six inches, more or less) from the ends of the cylinder, so that they are closed by the piston before it reaches the ends of the cylinder, so that said ports are closed by the piston, and the imprisoned air forms a cushion for the piston at the ends of its strokes, to prevent the jar that might be occasioned by impingement against the heads of the cylinder. I prefer to form the eduction-ports *F²* of a number of small holes, as shown in Fig. 4, to prevent wear or other injury to the piston-packing.

The front end or head of the cylinder is shown at *F⁴*, and the rear head at *F⁵*. The front head has a central disk, *F⁶*, capable of turning in the rim part of the head, and having two stuffing-boxes, *F⁷*, through which pass the duplicate piston-rods *W'* of the piston *W*. These rods work in a guide-frame, *X*, and carry at the ends a socket head or heads, *Y*. As shown, a single socket-head, *Y*, is connected to both piston-rods in the manner of a cross-head, and containing three sockets, *w*, for three picks. (See Fig. 6.) The socket-head *Y* is held upon the piston-rods *W'* by set-screws *y*, or by other suitable means. A supplemental socket-head, *Z*, may be fitted into either of the three sockets *w* in the absence of drill-picks *b*, and the latter be held in the sockets of head *Z*. The socket-head *Z* may be set at any angle with that of *Y*.

Fig. 6 shows the picks in a row, the outer ones, *b*, being similar in shape, except that they are made right and left. The picks *b* have one straight corner, *b²*, ending in an angular or square point, *b³*, from which extend at an acute angle two sharp edges, *b⁴b⁵*. Cutting at a right angle to each other on the inner side are extensions or wings *b⁶*, which, when no central

pick, b' , is used, come nearly or quite in contact with each other in case a central pick is used. (See Fig. 6.) The wings come nearly or quite in contact with the same. In case any material should become jammed fast between the picks, the next blow would force the object past the point of the wings, when it would be free to drop out.

A single wide-spreading pick may be used, as shown in Fig. 7. This has spreading sides ending in square points, and with a generally recessed or concavely-curved edge between the points, with small convexly-curved portions near the points.

15 l is a lamp attached to the frame X , or to the cylinder-head, and l' is a reflector for the same. The lamp is so placed as to throw light upon the place being operated upon.

The operation is as follows: The compressed air, entering both valve-chests E and R , drives first the small engine S , which works the slide-valve V , and then the pick-engine. The cylinder may be readily inclined upward or downward, or to either side, by means of the handles G^2 . 25 The machine may be pushed forward, and will retain its advanced position, (except as to the slipping of the wheels upon the platform,) owing to the friction-brake preventing the retrograde rotation of the wheels. To allow the retreat of the machine the brakes are raised from the friction-rings. The elevation of the cylinder may be changed, either by changing the length of the crank by means of device shown at $c' c^2$, or by means of the rods G and screws H , or 30 adjusting both these devices. The adjustment of the balance of the cylinder upon the wheels is had by the same means. The center of gravity of the cylinder F and attached parts is in all positions of the cylinder below the center 35 of the wheels, and consequently the machine will be steadily supported on the wheels. To 40

turn the guide-frame the disk F^6 may be turned after the cylinder-head bolts F^8 are loosened.

I claim as my invention—

1. The combination of pick-engine cylinder F , crank-axle C , hinged thereto, and the supporting-wheels B , for the purpose set forth. 45

2. The combination of cylinder F and crank-axle C , arms or rods G , and screws H , for the purpose set forth. 50

3. The single piston W , provided with two piston-rods, W' , and picks b , as set forth. 55

4. The combination, with the paired piston-rods W' , of the socket-head Y , securing said rods together, and constructed to receive and retain picks or supplemental socket Z , as set forth. 60

5. The combination, with the two wheels B of a mining-machine, of the friction-brake hung eccentrically to the wheels, and constructed to prevent their retrograde rotation, substantially as set forth. 65

6. The combination, with the engine-cylinder F , of the distinct induction-ports F' and eduction-ports F^2 , with separate valves v and v' , for the purpose set forth. 70

7. The two picks b , constructed with inward extensions or wings b^6 , and attached to duplicate piston-rods W' , substantially as and for the purpose set forth. 75

8. The combination of wheel-spindles c , sockets c' , and crank-arms c^2 of crank C , box D , and chest and cylinder $E F$, substantially as and for the purpose set forth.

9. The plate or tray A , formed with side guides, a , and adapted to lie on the floor of the mine, as set forth. 80

BENHARD YOCH.
